UNITED STATES PATENT OFFICE.

JACOB E. NEAHR, OF HARTSDALE, NEW YORK.

MATCH SAFE.

Application filed June 24, 1924. Serial No. 722,029.

This invention relates mainly to combined match-holders and ash-receivers, and also to an improved cover for an ash-receiver, provided with a cigar-quencher.

Safety matches are commonly supplied to smokers in the form of cardboard or paper strips slitted to form match stems, which are separately provided with striking heads, the strips being secured to one another at their bases, and the whole being enclosed in a flexible paper wrapper having a large end for the match-heads and a small end within which are confined the attached base portions of the strips; the whole usually forming a unit thick at one end and thin at the other end, and its sides being provided with prepared match-striking surfaces.

An object of the invention is to provide means for safely holding such match-packets upon a smoker's utensil, so that the utensil and packet can be served together to a guest or other user, and to effect this result in a simple and inexpensive manner, and produce an attractive device.

Other features and advantages will hereinafter appear.

In the accompanying drawings,

Figure 1 is a plan showing the packet clipped between the ash bowl and tray, and also showing the improved cover upon the bowl.

Figure 2 shows in sectional elevation the cover for the ash receiver or bowl.

Figure 3 is a part sectional elevation of the devices seen at Figure 1.

A broad-bottomed ash-receiving bowl 10 is mounted upon the bottom 11 of an ash-tray 12 by means of a shortened pedestal 13, to leave a narrow opening 14 between the tray and the bowl. The broad bottom of the bowl diverges a little from the tray bottom, and co-operates therewith to form a clip 15 into which to thrust the thin end 16 of the described packet 17 of matches 18. To confine the packet in this clip, it is only necessary to insert the same, narrow end 16 first

under the bowl 10, at any point around the bowl, and then press the packet inwardly or toward the center of the tray, thereby obtaining a pinching grip upon the packet, which holds it from becoming accidentally loosened. The brim 19 of the ash-tray rises considerably above the level of the bottom of the ash-receiving bowl 10, and the outer end of the packet 17 is flexed up a little (Figure 3) when inserted in the clip, the in-

ner end of the packet being thrust in about horizontally between the bottom of the tray and the bottom of the ash-receiving bowl, and the outer end of the packet being directed upwardly and outwardly over the brim 19 of the ash-tray upon which it rests.

The short pedestal 13 is preferably depressed from the bottom of the bowl by pressing down the central portion thereof, and this pedestal may be soldered or riveted or otherwise secured directly upon the floor of the ash-tray, preferably centrally thereof, the tray and bowl being preferably circular. The height of the pedestal may be substantially equal to or a little less than the thickness of the thin end of the packet, say about one-eighth of an inch, so that the packet when thrust into this annular clip may be pinched and held thereby.

There is also disclosed a cover 20 for the ash-bowl, which may be formed in one piece of sheet-metal, and upon which may be pivoted at 21 a single combined cigar-rest and cigar-extinguisher 22, the same being mounted at one side of the cover, and having an opening 23 for ashes extending from said cigar-extinguisher across the cover substantially to the other side thereof, so that the entire width of the cover is filled by the opening and the cigar-extinguisher. The extinguisher is provided at its outer end with a finger-piece 24, which is depressible to raise the inner end of the extinguisher, to permit the cigar to be inserted under the same, whereupon the extinguisher can be pressed down to pinch the cigar against the top of the ash-receiver. The extinguisher has weighted sides 25 extending down through said cover 20. To retain the cover, it may be provided with a pendent annular flange 26, fitting within the brim 27 of the bowl.

Variations may be resorted to within the scope of the invention, and portions of the improvements may be used without others.

Having thus described my invention, I claim:

1. A clip for a flexible packet of the described matches, comprising an ash-receiving bowl having a broad bottom, an ash tray, and a pedestal connecting said tray to said bowl, with the tray in close proximity to the bottom of the ash-receiving bowl and coacting therewith to clip firmly the thin end of the described flexible packet thrust between the bowl and the ash-tray.

2. A clip for a flexible packet of the de-

scribed matches, comprising an ash-receiving bowl having a broad bottom, an ash tray, and a pedestal connecting said tray to said bowl, with the tray in close proximity to the bottom of the ash-receiving bowl and coacting therewith to clip firmly the thin end of the described flexible packet thrust between the bowl and the ash-tray, said ash-tray having a brim rising above the bottom of the bowl and flexing the match-packet upwardly, to increase the grip of the tray and bowl upon the packet.

3. A clip for a flexible packet of the de-

scribed matches, comprising an ash-receiving bowl having a broad bottom, an ash tray, and a pedestal connecting said tray to said bowl, with the tray in close proximity to the bottom of the ash-receiving bowl and coacting therewith to clip firmly the thin end of the described flexible packet thrust between the bowl and the ash-tray, said pedestal in the form of a depression in the bottom of the bowl and firmly secured to the ash-tray.

JACOB E. NEAHR.
